TUBE ROLLING MILL

Richard E. Brock, Ambridge, Pa.

Application July 6, 1938, Serial No. 217,665

5 Claims. (Cl. 80—13)

My invention is an improvement in the manufacture of seamless tubing and involves the method and means for simultaneous interior and exterior reduction, elongation and smoothing of the wall of a pierced billet or tubular work piece, in transit through the mill.

Instead of usual standard practices employing outer compressing rolls and a uniform diameter mandrel or a mere shouldered enlarging mandrel, I utilize a surrounding group of diagonally acting skew rolls each having an initial taper and a truly cylindrical extension with an interposed co-operating mandrel of special construction.

Such mandrel is so made as to provide, in combination with the skew rolls, three successive zones of mutual external and internal treatment, to wit, (1) an entering preliminary inwardly and outwardly applied gauge reducing zone, (2) an abruptly adjacent final inwardly applied reducing zone, and (3) an inwardly and outwardly applied finishing or smoothing zone, practically parallel with the pass line.

In practicing my improved process or method, I utilize a mill and its parts like that shown in the accompanying drawings, in which:

Fig. 1 is a view of the mill in side elevation, partly broken away;

Fig. 2 is a plan view of Fig. 1;

Fig. 3 is a cross section on the line III—III of Fig. 1;

Figs. 4 to 7 inclusive are sectional detail views of the blank in progress, illustrating successive steps or zones of treatment by the skew rolls and co-operating mandrel;

Fig. 8 is a cross sectional view on the line VIII—VIII of Fig. 1 through the skew rolls but showing reinforcement of each by backing up rolls.

Referring to the drawings the mill is generally of conventional construction, utilizing a drive housing A the main driving gear of which is connected by shaft 2 with any suitable prime mover or source of power, as a motor B. The reduced speed gears of the drive housing are connected by shafts 3 and universal couplings 4 with the spindles 5 which are similarly connected at 6 with the shafts 7 of the several skew rolls, mounted in roll housing C. Beyond the roll housing C is the usual thrust bracket D, slidably mounted with usual adjusting and locking mechanism, on the foundation 8, to which the above mentioned main power imparting and roll housing elements are secured.

Rotatably mounted in the side plates 9 of roll housing C are the several skew rolls 10 comprising

the outer surrounding group, in suitable adjustable bearings, each being sufficiently diagonal to the normal line of the main pass to effect longitudinal feed of the work piece co-extensive with their external wall-reducing function. At 5 their forward or entering ends each roll 10 is preferably initially rounded at the terminal of a tapered substantially half length portion 11, beyond which the roll is continuously cylindrical as at 12.

The mandrel 13 is generally cylindrical, having a front preliminary entering extension 14 provided with a taper corresponding generally to that of front section 11 of the skew rolls; a midway abruptly tapered annular shoulder 15; and a 15 truly cylindrical rear extension 16 parallel with the section 12 of the skew rolls.

The mandrel 13 engages by a terminal rear socket 17, or otherwise, with the mandrel bar 18, the rear end of which is removably resisted by 20 the thrust bracket D, for separation and from the mandrel with the finished tube. Such parts are well known in the art.

The gears of the drive housing A are of any suitable arrangement for transmission of power 25 and desired speed from the prime mover B to the skew rolls 10, either direct as shown, or with an intervening speed reducer of suitable type, depending on working conditions.

Thus, as in Fig. 3 I show a cross section of the 30 drive housing in which the drive shaft 2 is provided with a pinion 19 engaging the several gears 20 of each shaft 3 for simultaneous rotation of the several skew rolls 10 through the converging spindles 5 and their universal joint connections. 35

The tubular blank or work piece E having been positioned as in Fig. 4 is initially gripped by the tapered portions 11 of the skew rolls which rotate and feed it forwardly with an initial tapered external compression. The blank is thus advanced until its approaching end engages the active portion of the tapered terminal 14 of mandrel 13, resisted by bar 18 and thrust bracket D.

Further forward movement of the blank by and between the tapered portions of the skew rolls and over the tapered end 14 of the mandrel effects simultaneous substantially equal external and internal reduction and gradual progressive thinning of the annular wall up to the annular 50 shoulder of the mandrel, as in Fig. 5.

Thereafter, while still confined by the taper faces 11 of the skew rolls, the blank is abruptly enlarged interiorly to its final inside diameter, and with its outside diameter already finally re- 55

duced, just prior to passing onto the cylindrical portion 16 of the mandrel and between the similar portions 12 of the skew rolls, as in Fig. 6.

Then the tube in progress is smoothed and 5 polished to its final finished surfaces in uniform continuous final condition.

If desired, the tube may then be subjected to additional treatment for straightening, sizing or further reduction or to cold drawing, as is well 10 known to those skilled in the art.

The simultaneous reduction of outside diameter and increase of inside diameter of the work piece and its resulting elongation, with accompanying condensation and final smoothing and polishing 15 of the finished tube, continues until its rear end has passed entirely beyond the mandrel. It will thus be seen that the pass of the mill narrows or decreases in external diameter and increases in internal diameter until it enters the third or 20 smoothing zone.

The thrust bracket is then withdrawn and the finished tube, mandrel bar, and mandrel are removed and separated, such bar and another mandrel being then replaced for the next similar 25 operation.

Trial operations of the mill have demonstrated its success and of the improved method of rapidly forming seamless tubing, as disclosed herein. Thus, with an original pierced billet or work piece 30 of the following dimensions, to wit:

	Inches
Outside diameter	1.223
Inside diameter	.750
Wall thickness	.2365
35 Area of wall	.7315

the resulting tubing, with greatly increased elongation, was:

	Inches
40 Outside diameter	1.062
Inside diameter	.876
Wall thickness	.093
Area of wall	.282

with the following relative or proportionate 45 changes, compared to the dimensions of the blank:

	Per cent
Reduction in area	61.4
Reduction in wall thickness	60.6
50 Increase in length	112.5

While properly proportioned skew rolls are ordinarily quite efficient for usual normal operations in the smaller sizes of tubing, they may be 55 resisted against outwardly exerted resistance forces by any suitable construction of backing rolls 21, as in Fig. 8. These may be mounted in the roll housing in any suitable manner, similar to like rolls in modern rolling mill practice, to 60 ensure continuous and accurate efficiency and effectively prevent deflection or breakage, and would contribute towards a more substantial mill.

What I claim is:

1. Means for forming seamless tubing from a

pierced billet or work piece consisting of a plurality of outer rotatable reducing skew rolls each having a front preliminary uniformly tapered portion and a finishing cylindrical portion, and an inner rotatable expanding mandrel having a 5 uniformly tapered end merging into an intermediate abruptly enlarged annular shoulder and a rear maximum diameter cylindrical portion parallel with and in final operative relation to the cylindrical portion of the outer rolls with an 10 intervening finishing pass therebetween.

2. Means for forming seamless tubing from a pierced billet or work piece consisting of a plurality of outer rotatable reducing skew rolls each having a front preliminary uniformly tapered 15 portion and a finishing cylindrical portion, back up rolls for the skew rolls, and an inner rotatable expanding mandrel having a uniformly tapered end merging into an intermediate abruptly enlarged annular shoulder and a rear maximum diameter cylindrical portion parallel with and in final operative relation to the cylindrical portion of the outer rolls with an intervening finishing pass therebetween.

3. Means for forming seamless tubing from a 25 pierced billet or work piece consisting of a plurality of outer rotatable reducing skew rolls each having a front preliminary uniformly tapered portion and a finishing cylindrical portion, and an inner rotatable expanding mandrel having a 30 uniformly tapered end merging into an intermediate abruptly enlarged annular shoulder co-extensive in its extreme diameter with a rear maximum diameter cylindrical portion, said tapered end and annular shoulder opposing pressure of the tapered portions of the skew rolls and the cylindrical portion of the mandrel opposing pressure of the cylindrical portions of the 35 skew rolls.

4. Means for forming seamless tubing from a 40 pierced billet or work piece consisting of a plurality of outer rotatable reducing skew rolls each having a front preliminary uniformly tapered portion and a finishing cylindrical portion, and an inner rotatable expanding mandrel having a 45 uniformly tapered end merging into an intermediate abruptly enlarged annular tapered shoulder co-extensive in its extreme diameter with a rear maximum diameter cylindrical portion, said tapered end and annular shoulder opposing pressure of the tapered portions of the skew rolls and the cylindrical portions of the mandrel opposing pressure of the cylindrical portions of the 50 skew rolls whereby to effect simultaneous external reduction and internal increase of diameter of the piece with final smoothing.

5. The construction as in claim 4 characterized by reinforcement for the skew rolls in the form of a series of outer resisting back up rolls 55 in contact with the several skew rolls.

RICHARD E. BROCK.
